UNITED STATES PATENT OFFICE.

SARAH M. KERN, OF PORTLAND, OREGON, ADMINISTRATRIX OF JOHN W. KERN, DECEASED.

RANGE-FINDER.

SPECIFICATION forming part of Letters Patent No. 742,038, dated October 20, 1903.

Application filed May 16, 1901. Serial No. 60,605. (No model.)

To all whom it may concern:

Be it known that I, SARAH M. KERN, a citizen of the United States, residing at Portland, in the county of Multnomah and State of Oregon, am the administratrix of the estate of JOHN W. KERN, deceased, late a citizen of the United States, who invented certain new and useful Improvements in Range-Finders; and I do hereby declare the following to be a full, clear, and exact description of the invention, such as will enable others skilled in the art to which it appertains to make and use the same.

The invention has for its object to provide simple and effective means whereby in a certain and ready manner to ascertain the distance of an object from the point of observation or to locate a point at a desired distance from that of observation.

Briefly stated, the invention comprises two telescopes, one of which, at least, must be pivotally mounted to permit its being moved at an angle with relation to the second telescope in order that both telescopes may be focused upon a common distant object. Combined with the movable telescope and operatively connected therewith to receive movement therefrom is a hand or pointer adapted to be moved over the graduated surface of a distance-indicator, and the mechanism intermediate the distance-pointer and the movable telescope is so proportioned and arranged that when the pivoted telescope is moved from its initial position and brought to a focus upon a distant object previously brought within the focus of the stationary telescope the distance-pointer will be so moved from its initial position with relation to the pivoted telescope as instantaneously to indicate upon the distance-dial the remoteness from the finder of the object sighted.

In the one embodiment of the invention shown a bed-plate carrying two telescopes is employed, one of the telescopes being rigidly fixed on the bed-plate and at exact right angles to its base-line and the other normally parallel with the first-named telescope, but adapted for pivotal movement on the bed-plate to permit adjustment to bring an object seen through the fixed telescope into the range of the movable telescope, a graduated

dial bearing distance-marks suitably arranged thereon, a pointer to traverse the dial, and motion-transmitting mechanism connecting the movable telescope and the pointer, whereby the movement of the movable telescope will actuate the pointer to indicate on the dial the distance of the range-finder from the object under observation.

The adjustment of the movable telescope will of necessity be very slight in sighting objects at long range—say from one to five miles—so that without the provision of means for multiplying the distance traversed by the movable end of the movable telescope it would not be possible to determine accurately by the slight movement of the pointer the distance measured. To provide for this, suitable means are provided—in the present instance a micrometer-screw, which is operatively connected, respectively, with the movable telescope and with the pointer. The micrometer-screw referred to comprises two screws or worms on a single shaft or bar, the screw coacting with the movable telescope having, say, one hundred threads to the inch and that coacting with the pointer ten threads to the inch. Thus a movement of the telescope through the arc of a circle of one one-hundredth of an inch will cause movement of the pointer through an arc of a circle of several inches, thereby permitting the distance-marks on the dial to be widely spaced apart, and thus rendered easy to read. In combination with the base-plate there may be suitable mechanism for elevating, depressing, and rocking the plate laterally and longitudinally and in addition a tangent-screw, by which arrangement the device will be adapted for use as a transit or surveyor's instrument in running lines, determining distances, or for other purposes in which the ordinary theodolite is employed. When used as a transit or theodolite, a suitable tripod will be provided, and, if desired, a compass may be combined with the bed-plate.

When used as a range-finder pure and simple, the elevating, depressing, and tilting mechanism mentioned and hereinafter to be fully described is suitable when the instrument is employed in connection with military operations—that is, for finding the range for

artillery upon the land. When, however, the finder is to be used at sea, the motion of the vessel renders that mechanism inefficient, so that the same or a part thereof may be dispensed with and the base-plate supported upon a swinging or universal joint and be so counterweighted as to remain constantly in a level position irrespective of the rolling or pitching of the vessel. One finder may be provided for a group of guns upon the ship, or, if preferred, each gun may be furnished with a separate finder. In the latter instance the finder may be mounted upon the turret or carriage of the gun, with the fixed telescope pointed in a direction exactly parallel with the line of fire, so that when that telescope is focused upon the object and the range has been determined by means of the movable telescope and its attendant mechanism it will only be necessary to elevate the barrel of the gun in order to give the desired trajectory to the projectile.

One of the important advantages of this invention is that by providing a bed-plate 25 or other support with two telescopes, each mounted on the bed-plate or support and arranged in sufficient proximity to each other to permit of being rapidly operated by a single operator, the transmission of telephonic signals or audible signals, such as are usually necessary in the employment of range-finders now in use, is obviated.

Before proceeding with the description of the device it may be noted at this point that 35 in the practical application of the principles embodied in this invention to a working machine the known ratios of expansion and contraction between different metals employed in its construction will be observed, so that 40 errors in calculation which might arise were the knowledge of these ratios not observed will be prevented.

In the accompanying drawings, forming a part of this specification, and in which like 45 letters of reference indicate corresponding parts, there is illustrated a form of embodiment of the invention in which it is shown as adapted for use as a range-finder for vessels and also for surveying purposes, it being understood that the same ideas may be 50 carried into effect in connection with other forms of device without departing from the spirit of the same.

In the drawings, Figure 1 is a view in plan 55 of a device when used either as a transit or as a range-finder, exhibiting the bed-plate, indicating-dial, and telescopes. Fig. 2 is a similar view with the dial removed, exhibiting the mechanism by which motion may be 60 imparted to the pointer. Fig. 3 is a view in elevation taken from the right-hand side of the machine and looking in the direction of the arrow 1 in Fig. 2. Fig. 4 is a view in elevation looking in the direction of the arrow 65 2, Fig. 2. Fig. 5 is a view in elevation of a part of the device looking in the direction of the arrow 3, Fig. 2. Fig. 6 is a horizontal

sectional view of the elevating, depressing, and swinging mechanism, taken on the line 4 4, Fig. 5. Fig. 7 is a sectional detail view 70 of a tangent-screw by which fine adjustment of the bed-plate may be effected in the running of lines or the like.

Referring to the drawings, A designates generally the bed-plate, which may, as shown, 75 be an open-work structure made of any suitable material, such as iron, aluminium, brass, or any other material suited to the purpose. This bed-plate may be mounted in any suitable position for operation, as upon the carriage of a gun or in the port-hole of a vessel or upon a tripod, the latter being employed where the device is used for surveying purposes.

While the device herein shown is not exhibited as associated with a compass, it is to be understood that the same may be employed where the device will be used for running lines in landwork.

The bed-plate A is provided on its upper 90 surface with two levels a a^2 , arranged at right angles to each other, these being used when the device is employed for surveying purposes and may, if desired, be omitted when the device is used as a range-finder, as it will be obvious that any leveling of the device independent of the vessel will be impracticable on the high seas. Upon the upper side of the bed-plate are mounted two telescopes B and B^2 , the telescope B being rigid with relation 100 to the bed-plate and arranged exactly at right angles to its base-line or rear edge and the telescope B^2 being mounted for pivotal movement at its front end upon the bed-plate and being moved at its rear end through mechanism hereinafter to be described. The telescopes are, as usual, provided with suitable cross-wires by which to center an object and with adjustable lens, as will be understood. Adjacent to the fixed telescope B and in line 110 with each other are arranged two standards or initial direction-finders b, each comprising a rod of metal having its upper end polished or burnished, by which to present an object readily attractive to the eye.

Each of the telescopes B and B^2 is supported upon a suitable casting b^3 , this casting in the case of the movable telescope B^2 being pivotally secured at its forward end to the bed-plate or casting A. The rear end of the casting of telescope B^2 is provided with a bearing b^4 , comprising a frame b^5 and a pivoted block b^6 , capable of swinging laterally and formed with a threaded opening adapted to be engaged by the threads on one end of a 125 rod b^7 . Mounted also upon the bed-plate and between the telescopes, preferably in close proximity to the movable telescope B^2 , is a circular casing D, having a dial d laid off in requisite divisions, as feet, yards, and miles, 130 these being arranged upon a series of concentric circles, as shown in Fig. 1. Pivotally mounted upon the side of the casing or upon the bed-plate immediately adjacent thereto

- is a sector-wheel C, having a long arm c^2 extending within the casing and a short arm without the casing, the latter arm being provided with a toothed edge c , these teeth being 5 engaged by a worm-gear upon the rod b^4 . Mounted centrally within the casing is a pointer or hand d^2 , carried by the shank of the pinion d^5 , mounted in bearings d^6 beneath the dial, the pinion being engaged by the 10 toothed portion c' of the long arm c^2 of the sector-wheel. The indicating-hand of the pointer d^2 is provided with an open portion d^3 , in which is secured a wire d^4 , arranged radially to traverse the concentric circles of the dial. 15 The threads upon the rod b^4 , engaging the bearing b^3 , will in this instance be one hundred to the inch, and the threads of the worm engaging the sector-teeth c will be, say, ten to the inch, and the relative lengths of the 20 respective arms of the sector-wheel will be so proportioned that by the movement of the movable telescope a distance of one one-hundredth of an inch under the action of the twisting motion given to the rod b^4 the 25 pointer d^2 will be caused to move through an arc upon the dial of ten inches, by which multiplication of movement the reading of the measurements ascertained will be rendered clear and easy. 30 To prevent backlash or any jarring of the hand or pointer d^2 , the pinion d^5 meshes with a gear-wheel d^7 , the pivots of which are mounted in a suitable casting d^8 , also beneath the dial, a coiled spring d^9 , secured at 35 one end to the supporting-plate of the wheel d^7 , as shown in dotted lines at d^{10} , and at the other end of the stud of the wheel, serving to take up any lost motion or play that would exist between the teeth of the pinion d^5 and 40 the toothed sector c' , thereby causing the pointer d^2 always to traverse the dial in a steady and regular manner.
- As shown in Fig. 1, the dial is marked off into five concentric circles, which are divided 45 off in divisions of feet, yards, and miles, as will be understood by reference to the said figure. The arm c^2 of the sector C carries a vertical pin or pointer c^3 , which projects through a curved slot c^4 in the dial, the 50 wall of this slot being laid off in divisions from "1" to "6," these divisions corresponding to the circles on the dial. Initially or when an observation is to be taken the pointer d^2 and c^3 will point, respectively, at the zero-mark on 55 the large dial and on the curved slot c^4 . When the pointer d^2 is moved by the micrometer-screw through the arc of a large circle, the pointer c^3 will be moved through the arc of a smaller circle. The function of the 60 pointer c^3 and its scale, which will be herein-after referred to as a "scale-indicator," is to determine which circle on the large dial is to be inspected to determine the reading. Thus, for instance, if the small pointer is between 65 "0" and "1" the reading will be found on the outer or first circle; if between "1" and "2" the reading will be on the second circle,

and if between "2" and "3" the reading will be on the third circle, and so on. In practice all readings from a greater distance than twelve hundred feet will be found on the first or outer circle.

The circular micrometer-head E, carried by the rod b^4 , to which it is secured by the milled thumb-nut E', has its periphery marked off into a suitable number of divisions, preferably one hundred, as shown, to form a scale for reading the fraction of revolution of the rod b^4 . Secured by means of a bracket upon the bed-plate and coöoperating with the micrometer-head E is a segmental scale e, forming a vernier and marked off in this instance into ten divisions, these ten divisions being exactly equal to nine of the divisions upon the micrometer-head E, thus permitting a reading to one-tenth of the latter divisions.

When the pointer upon the large dial has been brought to the zero-point, the nut E' is loosened to permit the head E to be turned upon the rod b^4 in order to bring the zero-point upon said head and upon the vernier-scale into registry, when said nut is screwed down to secure the head to the rod and may then be used to turn the rod in finding the range.

The micrometer-threads being a distance of one one-hundredth of an inch apart, the scale E permitting a reading of one one-hundredth of this distance and the vernier-scale allowing a reading to one-tenth of a division of the scale E, it will be seen that the movement of the telescope B² of one one-hundred thousandth of an inch may be read, so that the angular changes caused thereby while very small are easily read.

The object of the micrometer-head E and vernier-scale e is to locate a point at a desired distance from that of observation—that is to say, should it be desired to locate a point at one mile or farther from the operator this disk and scale will then come into use, the marks on the micrometer-head and vernier-scale indicating the micrometer-screw reading. Thus should it be desired to locate a point five miles distant, or eight thousand eight hundred yards on the dial, the screw will be moved until it indicates 21.96. Then by sighting the telescopes to bring the cross-wires to bear upon a point at that distance five miles will be located. If it be desired to locate a point, say, three miles distant, or five thousand two hundred and eighty yards on the dial, the screw will be moved until it indicates 36.6. Then by sighting the telescopes to bring the cross-wires to bear upon a point at that distance three miles will be located. If it be desired to locate a point, say, four thousand yards distant on the dial, the screw will be moved until it indicates 48.31. Then by sighting the telescopes to bring the cross-wires to bear upon a point at that distance four thousand yards will be located. Secured to the under side of the bed-plate are brackets F, shown provided with

journal-bearings supported on journals carried by a standard f . The standard f is provided at its lower end with a ball f^2 , (shown in dotted lines in Fig. 5,) engaging a ball-socket G , carried by the base-support g . A four-arm spider g^2 is supported on leveling-screws g^3 , having each their lower end provided with a ball engaging a ball-socket in the base-support. The spider is mounted to turn on the standard, but is held from longitudinal movement thereon, as by shoulders on the standard. A collar f^4 closely fits the standard f and carries a set-screw f^5 for locking it thereto. A tangent-screw f^6 , shown carried on the spider g^2 , engages said collar, thus providing precise means for adjusting the bed-plate in an arc about a vertical axis. To one of the brackets F is attached a graduated sector arranged to be traversed by the pointer carried by an arm a^3 , depending from the adjacent journal. The function of this sector and pointer is to determine when the bed-plate is approximately level. Any further adjustment to secure a perfect leveling of the base-plate is effected through the leveling-screws above described. For rocking the bed-plate on its supporting-journals a tooth-sector a^4 , depending from the bed-plate, is arranged in mesh with a worm f^{11} , journaled in a hanger f^{10} , secured to one of the journals supporting the bed-plate and provided with an operating-crank f^9 . For permitting the bed-plate to swing about a vertical axis, the base-support g is rotatably carried in a frame g^x . A toothed sector f^7 , secured to the base-support, is arranged in mesh with a worm f^8 , journaled on the frame g^x and provided with an operating-crank f^{12} . By the mechanism just described adjustment of the bed-plate in every conceivable direction is provided for, so that the device, as before pointed out, will be adaptable for use either as a range-finder on vessels or for surveying purposes on land.

The operation of the device thus described when used as a range-finder in military operations upon the land is as follows: The frame g^x being mounted upon any suitable support—such as a tripod, for instance—the worm-gear f^{11} is manipulated, by means of a crank f^9 , in order to bring the pointer carried by the arm a^3 upon the zero-point of the scale f^3 . The bed-plate is then leveled by means of the leveling-screws g^3 and the levels a^2 , the fixed telescope being pointed in the general direction of the object the range of which it is desired to ascertain. This fixed telescope is then pointed in a vertical line with said object by means of the coarse adjustment of the worm-gear f^8 , and if the object be not upon a plane with the instrument the worm-gear f^{11} is manipulated until the proper pitch of the fixed telescope is obtained. The cross-hairs in the telescope are then brought to bear exactly upon the object by means of the tangent-screw f^6 . The movable telescope B^2 is then manipulated, by means of the wheel carried by the rod b^4 , until its cross-hairs are

also brought directly upon the object. At the same time with this movement of the movable telescope the sector-wheel C is operated to cause the pointer d^2 to leave its zero position upon the dial b and travel there-around in the direction of the movement of the hands of a clock, and when the object has been focused upon the cross-hairs of the movable telescope the reading taken from the dial will give correctly the range of the object, these readings to be taken, as before explained, from the circle indicated by the position of the pin c^3 in the slot c^4 . From this reading the elevation of the barrel of the gun may be calculated, at the same time taking into consideration the angle of depression or elevation of the telescopes as read upon the scale f^3 .

When used as a surveyor's instrument, the manipulation of the leveling means will be similar to that above described, and the method of locating a point at a given distance heretofore described may be employed.

When used upon shipboard as a range-finder, either the positive leveling means or the gravitating and freely-swinging leveling means may be utilized, or one of such means may be substituted for the other to suit the prevailing conditions.

Having thus fully described the invention, what is claimed as new is—

1. In a device of the character described, the combination of a bed-plate, a fixed and a movable sighting device mounted thereon, an indicator, a rod journaled on said bed-plate and provided with threads of different pitch at its respective ends, and means operatively connecting said threaded ends to the movable sighting device and the indicator, substantially as described.

2. In a device of the character described, the combination of a bed-plate, a fixed and a movable sighting device mounted thereon, an indicator, a rod journaled on said bed-plate and provided with threads of different pitch at its respective ends, means operatively connecting said threaded ends to the movable sighting device and the indicator, and means for securing positive action and preventing backlash in the mechanism, substantially as described.

3. In a device of the character described, the combination of a bed-plate, a fixed and a movable sighting device mounted thereon, an indicator, a rod journaled on said bed-plate and provided with threads of different pitch at its respective ends, means operatively connecting said threaded ends to the movable sighting device and the indicator, and a spring-actuated wheel arranged and constructed to secure positive action and prevent backlash in the mechanism, substantially as described.

4. In a device of the character described, the combination of a bed-plate, a fixed and a movable sighting device mounted thereon, an indicator provided with a dial and pointer, a plurality of differently-graduated scales on

said dial in position to be traversed by said pointer, an auxiliary pointer and auxiliary scale on the indicator, said auxiliary scale containing a number of divisions equal to the 5 number of said differently-graduated scales, and so arranged that the position of the auxiliary pointer will determine the particular scale on which the reading of the indicator is to be taken, and means operatively connecting the movable sighting device and the indicator, substantially as described.

5. In a device of the character described, the combination of a bed-plate, a fixed and a movable sighting device mounted thereon, an 15 indicator provided with a dial and a pointer, a plurality of differently-graduated concentric circles on said dial in position to be traversed by said pointer, an auxiliary pointer and auxiliary scale on the indicator, said auxiliary scale containing a number of divisions equal to the 20 number of said differently-graduated scales, and so arranged that the position of the auxiliary pointer will determine the particular scale on which the reading of the indicator is to be taken, a toothed sector arranged in operative connection with said first pointer 25 and carrying said auxiliary pointer, a rod journaled on the bed-plate and provided with threads of different pitch at its respective ends, the threaded end of lesser pitch operatively connected to said movable sighting device and the threaded end of greater pitch 30 substantially as described.

6. In a device of the character described, the combination of a bed-plate, a fixed and a movable sighting device mounted thereon, an indicator provided with a dial and pointer, a plurality of differently-graduated concentric circles on said dial in position to be traversed 35 by said pointer, an auxiliary pointer and auxiliary scale on the indicator, said auxiliary scale containing a number of divisions equal to the number of said differently-graduated circles, and so arranged that the position of 40 the auxiliary pointer will determine the particular graduated circle on which the reading of the indicator is to be taken, means operatively connecting the movable sighting device and the indicator, and means constructed and 45 arranged to prevent backlash in the mechanism, substantially as described.

7. In a device of the character described, the combination of a bed-plate, a fixed and a movable sighting device mounted thereon, an 50 indicator provided with a dial and pointer, a toothed sector arranged to operate said pointer, a rod journaled on said bed-plate and provided with threads of different pitch at its respective ends, the threaded end of lesser pitch 55 operatively connected to said movable sighting device and the threaded end of greater pitch arranged in mesh with said toothed sector, and means constructed to prevent backlash in the mechanism, substantially as described.

60 8. In a device of the character described, the combination of a bed-plate, a fixed and a movable sighting device mounted thereon, an indicator provided with a dial and pointer, a toothed sector arranged to operate said pointer, a rod journaled on said bed-plate and provided with threads of different pitch at its

respective ends, the threaded end of lesser pitch operatively connected to said movable sighting device and the threaded end of greater pitch arranged to mesh with said toothed sector, and a spring-actuated wheel arranged and constructed to secure positive action and prevent backlash in the mechanism, substantially as described. 75

9. In a device of the character described, the combination of a bed-plate, a fixed and a movable sighting device mounted thereon, an indicator provided with a dial and pointer, a plurality of differently-graduated scales on 80 said dial in position to be traversed by said pointer, an auxiliary pointer and auxiliary scale containing a number of divisions equal to the number of said differently-graduated scales, 85 and so arranged that the position of the auxiliary pointer will determine the particular scale on which the reading of the indicator is to be taken, a toothed sector arranged in operative connection with said first pointer 90 and carrying said auxiliary pointer, a rod journaled on the bed-plate and provided with threads of different pitch at its respective ends, the threaded end of lesser pitch operatively connected to said movable sighting device and the threaded end of greater pitch 95 arranged in mesh with said toothed sector, and means constructed to prevent backlash in the mechanism, substantially as described.

10. In a device of the character described, the combination of a bed-plate, a fixed and a movable sighting device mounted thereon, an indicator provided with a dial and pointer, a plurality of differently-graduated scales on 105 said dial in position to be traversed by said pointer, an auxiliary pointer and auxiliary scale containing a number of divisions equal to the number of said differently-graduated scales, 110 and so arranged that the position of the auxiliary pointer will determine the particular scale on which the reading of the indicator is to be taken, a toothed sector arranged in operative connection with said first pointer and carrying said auxiliary pointer, a rod journaled on the bed-plate and provided with threads of different pitch at its respective 115 ends, the threaded end of lesser pitch operatively connected to said movable sighting device and the threaded end of greater pitch 120 arranged in mesh with said toothed sector, and a spring-actuated wheel arranged and constructed to secure positive action and prevent backlash in the mechanism, substantially as described. 125

11. In a device of the character described, the combination of a bed-plate, a fixed and a movable sighting device mounted thereon, an indicator provided with a dial and pointer, a plurality of differently-graduated scales on 130 said dial in position to be traversed by said pointer, an auxiliary pointer and auxiliary scale containing a number of divisions equal to the

number of said differently-graduated scales, and so arranged that the position of the auxiliary pointer will determine the particular scale on which the reading of the indicator is to be taken, a toothed sector arranged in operative connection with said first pointer and carrying said auxiliary pointer, a rod journaled on the bed-plate and provided with threads of different pitch at its respective ends, the threaded end of lesser pitch operatively connected to said movable sighting device and the threaded end of greater pitch arranged in mesh with said toothed sector, a scale carried by said rod, a vernier adjacent said scale, and means constructed to prevent backlash in the mechanism, substantially as described.

12. In a device of the character described, the combination of a bed-plate, a fixed and a movable sighting device mounted thereon, an indicator provided with a dial and pointer, a plurality of differently-graduated scales on said dial in position to be traversed by said pointer, an auxiliary pointer and auxiliary scale on the indicator, said auxiliary scale containing a number of divisions equal to the number of said differently-graduated scales, and so arranged that the position of the auxiliary pointer will determine the particular scale on which the reading of the indicator is to be taken, a toothed sector arranged in operative connection with said first pointer and carrying said auxiliary pointer, a rod journaled on the bed-plate and provided with threads of different pitch at its respective ends, the threaded end of lesser pitch operatively connected to said movable sighting device and the threaded end of greater pitch arranged in mesh with said toothed sector, a scale adjustably supported on said rod, means arranged to lock said scale in position on said rod, a vernier adjacent said scale, and means constructed to prevent backlash in the mechanism, substantially as described.

13. In a device of the character described, the combination of a bed-plate, a fixed and a movable sighting device mounted thereon, an indicator provided with a dial and pointer, a plurality of differently-graduated scales on said dial in position to be traversed by said pointer, an auxiliary pointer and auxiliary scale on the indicator, said auxiliary scale containing a number of divisions equal to the

number of said differently-graduated scales, and so arranged that the position of the auxiliary pointer will determine the particular scale on which the reading of the indicator is to be taken, a toothed sector arranged in operative connection with said first pointer and carrying said auxiliary pointer, a rod journaled on the bed-plate and provided with threads of different pitch at its respective ends, the threaded end of lesser pitch operatively connected to said movable sighting device and the threaded end of greater pitch arranged in mesh with said toothed sector, a scale carried by said rod, a vernier adjacent said scale, and a spring-actuated wheel arranged and constructed to secure positive action and prevent backlash in the mechanism, substantially as described.

14. In a device of the character described, the combination of a bed-plate, a fixed and a movable sighting device mounted thereon, a standard provided with a journal supporting said bed-plate, means for rocking the bed-plate on its journal, comprising a worm carried by said journal and an intermeshing worm-wheel secured to the bed-plate, a base-support for said standard, a frame on which said base-support is rotatably mounted, a toothed sector secured to the base-support, and an intermeshing worm journaled on said frame, substantially as described.

15. In a device of the character described, the combination of a bed-plate, a fixed and a movable sighting device mounted thereon, a standard provided with a journal supporting said bed-plate, means for rocking the bed-plate on its journal, comprising a worm carried by said journal and an intermeshing worm-wheel secured to the bed-plate, a graduated sector carried by the bed-plate, a pointer secured to the journal and arranged to traverse said graduated sector, a base-support for said standard, a frame on which said base-support is rotatably mounted, a toothed sector secured to the base-support, and an intermeshing worm journaled on said frame, substantially as described.

In testimony whereof I affix my signature in the presence of two subscribing witnesses.

SARAH M. KERN.
